WINDOW BLIND GUIDE

Lee Nelson, Manhattan Beach, Calif., assignor of
one-half to Henry J. Bagliazio, San Pedro, Calif.

Application October 2, 1950, Serial No. 188,030

4 Claims. (Cl. 160—268)

1

This invention is concerned with a window blind guide and is useful in connection with roller type window blinds or shades, it being a general object of the invention to provide a construction that is simple and practical for the purpose of facilitating the proper guiding of a web or blind onto its supporting roll.

Windows such as occur in walls of homes or buildings are commonly equipped with shades or blinds, and the usual device of this character is of the roller type and is mounted on or carried by the case of the window at the top or upper portion thereof. The usual blind involves a roller supported by brackets and the blind proper is in the nature of a flexible sheet or web, usually a fabric suitably treated or coated. The lower or depending edge of the usual blind is reinforced with a stiffening member and a cord or pull depends from the lower end of the web to facilitate operation thereof. Considerable care and skill is required to operate a web of the character mentioned accurately with reference to the roll, and when care and skill are not exercised, as is usually the case, the web winds onto the roll so as to cause an edge of the web to rub at an end of the roll and consequently become damaged or chafed. In practice the usual blind of the character referred to after being used but a short time has both edges more or less damaged, and thus rendered unsightly.

It is a general object of this invention to provide a guide or guiding construction which serves to so guide the web or blind proper onto its supporting roll as to eliminate the usual damaging of the web, even though it is operated casually and without the exercise of great skill or care.

Another object of this invention is to provide a combination of parts wherein a blind is related to guides which occur on a common frame or case and which are spaced from the supporting roll of the blind so that the blind is accurately guided with reference to the roll whenever it is operated.

Another object of this invention is to provide a simple unitary blind guide applicable to a window frame or case at a suitable point below a blind carried by that case and which serves to guide an edge of the blind and confine it, to the end that the blind can be operated repeatedly without damage or injury.

In the structure provided by the invention a window frame has vertical parts or sides and a header between the upper ends of the sides. A blind of the roller type is mounted on the upper portion of the frame, for instance, adjacent the header. The roller of the blind is mounted by means of suitable brackets and the web or blind

2

proper is carried on the roller and depends therefrom to extend between the sides of the case. A pair of guides is provided on the case, preferably the sides of the case, a suitable distance below the roller, and they are spaced apart so that the blind operates between them. Each guide involves a shoe with a guiding face, preferably convex in form, which face is engaged by an edge of the blind. Lips project from the sides of the shoe and are vertically disposed and spaced apart so that an edge portion of the blind is received and held between them, maintaining the edge of the blind in proper relation to the guide shoe. A mounting flange or base plate is provided on or in connection with the shoe and is applicable to the window case as by means of suitable fasteners or screws.

The various objects and features of my invention will be fully understood from the following detailed description of typical preferred forms and applications of the invention, throughout which description reference is made to the accompanying drawings, in which:

Fig. 1 is a view showing a wall having a window therein and showing a blind on the window case and blind guides related to the blind to maintain the web or blind portion thereof properly related to the roller thereof. Fig. 2 is an enlarged broken detailed sectional view taken in the direction indicated by line 2—2 on Fig. 1. Fig. 3 is a view taken as indicated by line 3—3 on Fig. 2. Fig. 4 is a view taken as indicated by line 4—4 on Fig. 3. Figs. 5, 6 and 7 are views illustrating a somewhat different form of the invention, wherein the blind is mounted within the case of the window rather than on the exterior of it. Fig. 5 illustrates one corner of the case, showing the mounting of the blind and the relationship of the guide thereto. Fig. 6 is an enlarged plan view taken as indicated by line 6—6 on Fig. 5, and Fig. 7 is an enlarged side elevation of the guide shown in Figs. 5 and 6.

In the drawings I have illustrated a wall W with a window opening therein provided with the usual case A. A roller type shade or blind B is carried by the case A and guides C are carried by the case and are cooperatively related with the web or blind proper of element B. The window case A being of typical or conventional construction has a lower element or sill 10, vertical elements or sides 11 and a transverse top or header 12 between the upper ends of the sides 11.

Referring to the form of the invention illustrated in Figs. 1 to 4, inclusive, the blind B is mounted on the exterior of the case A and is shown as involving a roll 20 carried by suitable mounting brackets 21 applied to the exterior of

the case. The web or blind proper 22 is carried on the roll 20 and, depending upon its position or degree of operation, it depends from the roll. The lower end 24 of the blind is preferably reinforced as by a stiffener and a suitable cord or pull 25 depends from the edge 24 to facilitate convenient operation. In the case under consideration the roll 20 is mounted so that it extends horizontally at the exterior of the header 12 of the window case and the blind 22 is of such width as to extend completely across the window opening so that its edges 26 overlap the sides 11 of the case.

The present invention provides a pair of guides, one on each side 11 of the case, and the guides are like opposed elements spaced a short distance, for instance a few inches, below the roll 20, and spaced apart a distance about equal to the width of the blind 22.

Each guide C preferably involves a shoe 30 opposing an edge 26 of the blind 22 and having a guiding face 31 that extends in the general direction of the guided edge 26. The face 31 is preferably convex in form and it may be pitched so that its upper end is close to or in guiding contact with the edge 26, while its lower end is spaced somewhat away from the edge 26.

Ears 33 project from the vertical edges of the shoe 30 and extend toward the blind 22 to overlap the edge portions thereof. The ears 33 are spaced apart, forming a channel in which the edge portion of the blind operates with substantial clearance and in the preferred form of the invention the inner or opposed sides 35 of the ears are convex in form and thus effectively 35 guide the edge portion of the blind, in the event that the blind is operated when deflected from a true vertical position. A mounting flange or base 38 carries or projects from the shoe 30. In the case illustrated the flange 38 is disposed relative to the shoe 30 so that it bears against the face of side 11 of the case A while holding the shoe 30 properly related to the edge of the blind 22, as clearly shown in Figs. 2 and 3 of the drawings. In practice any suitable means may be 45 employed to secure the flange 38 to the case. In the drawings I have shown openings 40 in the flange 38 carrying mounting screws 41.

In accordance with the preferred form of the invention each guide C as hereinabove described is a single unitary element, for instance, it may be a casting, and it is of such form that it can be advantageously manufactured in quantities and at little cost. Furthermore, it is to be observed that the guide or unit that I have provided is simple in action and is such that it can be easily and quickly mounted so it is related to a blind, as shown throughout the drawings.

In the form of the invention shown in Figs. 5, 6 and 7 the blind B' instead of being mounted on the exterior of the case A is mounted within the case at the upper end thereof to be adjacent to header 12. In this case guides C' provided by the present invention, instead of being mounted on the exterior of the sides 11, as shown in Figs. 1 to 4, inclusive, are mounted at the interior of the case. In this situation each guide C' may be advantageously formed with two mounting flanges 38', one projecting upwardly and the other downwardly, and each of these flanges may have a screw hole, as shown in Fig. 7 of the drawings. In other respects, that is, as to the formation of the shoe and ears, this form of guide may be the same as that first described.

In installing the guides C of the present in-

vention a short distance, that is, a matter of a few inches, below the roller 20, they are inconspicuous and are so located that they do not in any way inconvenience a user. The guides being located as shown in the drawings serve to effectively guide the blind onto the roller and the deflections of the blind incidental to usual operation are corrected and the blind is led or fed centrally onto the roller. With the guides of the present invention, a usual blind can be operated without great care or skill over a long period of time without the edges of the blind becoming worn or chafed, as is usually the case.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A blind guide applicable to a window case and engaged by a blind mounted at the case including, a unit having a guide shoe with a convex face opposing and guiding an edge of the blind, ears projecting from the shoe and toward the blind and spaced apart to receive an edge portion of the blind between them, and a mounting supporting the shoe in fixed position on the case, the said face of the shoe being pitched and defining an upwardly converging space in which the blind operates.

2. A guide applicable to a window case to guide a blind at the window including, a guide shoe, spaced opposed ears projecting from opposite edges of the shoe, and a mounting carrying the shoe and applicable to the case to support the shoe in fixed position with an edge of the blind guided by the shoe and confined between the ears, the shoe having a convex face opposing the edge of the blind.

3. A unitary guide applicable to a window case to guide a blind including, a guide shoe with a convex guide face at the front thereof, ears fixed at opposite edges of the shoe and projecting from the said face and having opposed convex blind guiding faces, and a mounting flange projecting from the rear of the shoe applicable to the case to support the shoe with the blind between the ears and guided by the said ears and face of the shoe.

4. A unitary guide applicable to a window case to guide a blind at the window including, a guide shoe, spaced ears projecting from opposite edges of the shoe, and a mounting carrying the shoe and applicable to the case to support the shoe in fixed position with an edge of the blind guided by the shoe and confined between the ears, the shoe having a convex face opposing the edge of the blind and upwardly inclined so that its uppermost portion closely approaches the blind and the ears having opposed convex faces and rounded outer ends.

LEE NELSON.
